F. P. PERDUE, OF ATLANTA, GEORGIA.

Letters Patent No. 88,898, dated April 13, 1869.

IMPROVED RAILWAY-SWITCH

The Schedule referred to in these Letters Patent and making part of the same.

To all whom it may concern:

Be it known that I, F. P. PERDUE, of Atlanta, in the county of Fulton, and in the State of Georgia, have invented certain new and useful Improvements in Railroad-Switches; and do hereby declare that the following is a full, clear, and exact description thereof, reference being had to the accompanying drawings, and to the letters of reference marked thereon.

The nature of my invention consists in the construction and general arrangement of a railroad-switch, which will be hereinafter more fully described.

In order to enable others skilled in the art to which my invention appertains, to make and use the same, I will now proceed to describe its construction and operation, referring to the annexed drawings, which form a part of this specification, and in which—

Figure 1 is a plan view, and

Figure 2 an end view.

A A' represent the rails of the main track, and B B', those of the side track.

The side-track rails are all stationary, but part of the main track, marked C C', is movable, so as to be changed from the main to the side track when so desired.

This is accomplished by rods D D, connecting the two rails C and C', and a crank-lever, E, which by means of hinged rod F, is connected with the rail C, another rod G, then connects the hinged rod F with one of the rods D, so that by turning the crank-lever E, the rails C and C' are moved at the same time to connect either with the main or the side track.

To the rail C is secured a rod, H, which operates the signal I, showing to the engineer of the approaching train, whether the switch is open or not.

By this means there is no danger of having wrong

signals, as the position of the signal-board is always depending upon the position of the switch.

At the point where the inner rails A' and B' of the two tracks should cross each other, is one movable rail J, which is turned from one to the other, forming connection on the main track or the side track, according to the position of the switch already described.

This movable rail J is secured at one end to a clamp, K, pivoted to the cross-tie, and at the other end connected by a rod, L, to a bent lever, M, which in its turn is connected by a rod, N, running under the middle rail B' to another bent lever O, which is operated by the lever E, the hinged rod F extending for that purpose to the said lever O, between the two rails of the main track.

It will be seen that by this arrangement, I operate the movable rail J at the same time as the rails C C' are changed.

I am aware that devices for simultaneously operating the frog, switch, and signal have been known before, hence, I do not broadly claim devices for this purpose.

What I claim, is—

The arrangement of the lever E, hinged rod F, bent levers O and M, and rods G and N, with the rails C C', and pivoted rail J, in combination with the rod H, and signal I, all substantially as and for the purposes set forth.

In testimony that I claim the foregoing, I have hereunto set my hand, this 1st day of August, 1868.

F. P. PERDUE.
